UNITED STATES PATENT OFFICE

HENRY H. HARRIS, OF DETROIT, MICHIGAN

HEAT TREATING RECEPTACLE

Application filed December 15, 1930. Serial No. 502,359.

My invention relates to metallic receptacles such as carburizing boxes and the like.

By my invention, I construct a sectional receptacle comprising one or more parts of 5 rolled, forged or pressed metal, as rolled sheet metal, for example, united by welding with parts of cast metal, so arranged and united that the more flexible sheet portion or portions absorb unequal strains in five- 10 sided containers to reduce deformation and failures in service. The preferred arrangement is one of alternation, as for example, cast pieces between sheet portions, and vice versa.

15 Objects of the invention include production of mechanically strong boxes, with improvement in capacity for resisting or absorbing strains incident to foundry practice and to heating and cooling in use, lightening of 20 the box as compared with all-cast boxes, and reduction in cost.

My invention will be best understood from the following description of constructions embodying the invention shown in the accompanying drawing, wherein

Figure 1 is a perspective view of a metallic receptacle consisting of cast end portions with a member of rolled, pressed, or forged (sheet) material welded into the sides and 25 bottom of the box between the cast end portions to connect the same.

Fig. 2 is an inverted perspective view of a metallic receptacle with a sheet member welded into the ends and bottom thereof to 30 connect cast side portions;

Fig. 3 is an enlarged sectional detail view taken on line 3—3 of Fig. 1;

Fig. 4 is a perspective view of a metallic receptacle similar to that of Fig. 1 having 40 end portions of cast metal with an intermediate portion of sheet metal, the latter constituting the main portion of the box walls;

Fig. 5 is a view similar to Fig. 4 in which the end portions are stamped sheets and the 45 main intermediate part is of cast metal;

Fig. 6 is a plan view of a metallic receptacle having a cast body and provided with forged or pressed corner portions; and

Fig. 7 is a view similar to Fig. 6 of a metallic receptacle the body of which is of stamped 50 sheet metal and the corners of which are cast and welded in place.

Referring to Fig. 1 of the drawing, reference character 10 designates the receptacle generally, which comprises two end portions 55 C_1, C_2 , preferably cast of chrome nickel alloy or the like, and joined together by welding a strip of rolled, forged, or pressed material S_1 of substantially the same analysis, to the edges thereof along the weld lines W_1, W_1 , 60 strip S_1 being preliminarily formed up into substantially U-shape to fit between the end members C_1, C_2 , and comprising side legs 12, 12, and a connecting web portion 14. This strip S_1 of sheet metal or the like serves to 65 take up the unequal strain resulting from high temperatures, and by forming a central corrugation or shallow beading portion 16 therein, a reinforcement is provided in addition to that produced by the welds. Electrical 70 welding is preferable, substantially V-shaped grooves G being formed between the parts to be united and filled with welding stick material 18.

In Fig. 2 the side portions C_3, C_4 of the 75 receptacle 10a are cast, and a strip of rolled, forged, or pressed material S_2 is welded at W_2 to the meeting edges of said portions along the welding grooves to join same. A shallow beading or corrugation 16a is pref- 80 erably also provided for reinforcement.

In these two forms, the cast portions make up the main part of the box.

In Fig. 4 I have shown relatively shallow 85 cast end portions C_5, C_6 with an interposed broad sheet metal portion S_3 welded therebetween and making up the main part of the box. Sheet part S_3 may be corrugated, or beaded, if desired, to give added strength, 90 also, if desired, the corrugation or beading of

Figs. 1 and 2 may be dispensed with, as in Fig. 4.

The form of Fig. 5 is similar to Fig. 4, but resembles Figs. 1 and 2 in that the intermediate broad cast portion C_7 forms the main part of the box and is interposed by welding between relatively shallow sheet metal end portions S_7 , S_8 , which may conveniently be stamped or forged into shape.

10 The form shown in Fig. 6 comprises a cast body C_9 having corners S_9 of preformed forged, rolled, or stamped material welded into grooves G_9 , while in the form shown in Fig. 7 a sheet body S_{10} has cast corners C_{10} welded in place in grooves G_{10} as indicated at W_{10} . The corner pieces preferably fill out a corner recess in the box bottom and also include a preferably fillet form upright portion that is interposed between the edges of 20 the end wall and side wall box parts.

In my invention, the receptacle being made of sections, such sections or portions can be of reduced weight compared to the weight of the corresponding parts of a receptacle 25 cast all in one piece. By the use of sections composed in part of sheet material and in part cast, strains from the cast portion or portions are transmitted to and absorbed by the flexing sheet portion or portions, the 30 structure thus formed being stiffer and stronger than one entirely composed of sheet material but more flexible than one which is entirely cast. My invention is particularly adapted for five sided containers in which 35 the bottom expands (or contracts) at a greater rate than the open portion of the container, this being liable to cause distortion and failure of the receptacle if entirely cast.

It will be understood that when boxes such 40 as shown are used in push furnaces they are inserted and the pushing forces are applied through the trays (not shown) forming the sixth side of the receptacle.

The term "sheet" is used in the claims as a 45 convenient designation for metal that is pressed, forged, or rolled.

Having described my invention, I claim:

1. A metallic receptacle for use in heat 50 treating furnaces comprising a plurality of integrally formed members each including partial bottom and vertical wall portions, certain of said members being of sheet metal and others thereof being cast, and said members complementing each other to form the 55 vertical and bottom walls of the receptacle and being welded together at the contiguous edges thereof.

2. A metallic receptacle for use in heat 60 treating furnaces comprising a plurality of integrally formed members complementing each other to form the vertical and bottom walls of the receptacle and welded together at the contiguous edges thereof, each of said members including partial bottom and vertical 65 wall portions, the depth of each vertical

wall portion being equal to the depth of the receptacle, and said members being in part of sheet metal and in part cast.

3. A metallic receptacle for use in heat 70 treating furnaces comprising integrally formed outer and intermediate members complementing each other to form the vertical and bottom walls of the receptacle and welded together at the contiguous edges thereof, each outer member including one vertical wall of the receptacle and portions of the other vertical wall and bottom wall of the receptacle, and the intermediate member including the remaining portions of the bottom and vertical walls of the receptacle, 75 said members being composed in part of sheet metal and in part cast.

4. Receptacle as claimed in claim 3 in which the vertical wall portions of the intermediate member comprise the main parts of 80 the side walls.

5. Receptacle as claimed in claim 3 in which the partial wall portions of the outer members comprise the main parts of the 85 side walls.

6. Receptacle as claimed in claim 3, in which the intermediate member is of sheet metal and the outer members cast.

7. A receptacle as claimed in claim 3 in which the intermediate member is of cast 90 metal and the outer members of sheet metal.

8. A receptacle as claimed in claim 3 in which the outer members are cast and the intermediate member comprises a relatively narrow strip of corrugated sheet metal.

9. A metallic receptacle for use in heat 100 treating furnaces comprising a cast body portion complete except at corners, and sheet metal corner members having vertical and bottom wall portions received into the corners to complete the body portion and welded in the corner places.

10. A metallic receptacle for use in heat 110 treating furnaces comprising a sheet body portion complete except at the corners, and cast corner members having vertical and bottom wall portions received into the corners to complete the body portion and welded in the corner places.

11. A metallic receptacle for use in heat 115 treating furnaces comprising a plurality of integrally formed members each including partial bottom and vertical wall portions, said members complementing each other to form the vertical and bottom walls of the receptacle and being welded together at the contiguous edges thereof.

12. A metallic receptacle for use in heat 120 treating furnaces comprising integrally formed outer and intermediate members complementing each other to form the vertical and bottom walls of the receptacle and welded together at the contiguous edges thereof, each outer member including one vertical wall of the receptacle and angularly 125

disposed portions of the other vertical walls and bottom wall of the receptacle, and other of said members including the remaining portions of the bottom and vertical walls of the receptacle.

13. Receptacle as claimed in claim 12 in which at least the outer members are of cast metal.

14. A metallic receptacle for use in heat treating furnaces comprising sheet portions and cast portions so meeting as to provide substantially V-shaped grooves, and metal substantially filling said grooves and securing the parts together.

15. In testimony whereof, I have signed my name hereto.

HENRY H. HARRIS.
